HAND MOUNTED ELECTRICAL MASSAGER

Samuel L. McNair, Overland Park, Kans., assignor to
Dazey Products Co., Kansas City, Mo.

Filed Aug. 28, 1973, Ser. No. 392,260

Term of patent 14 years

Int. Cl. D28—03; D24—99
U.S. Cl. D83—1 T

Fig. 1.

Fig. 2.

Fig. 3.

Fig. 4.

Fig. 5.

FIG. 1 is a top plan view of a hand mounted electric massager showing my new design;

FIG. 2 is a side elevational view of same, the other side being substantially the same in appearance;

FIG. 3 is an end elevational view taken from the left end of FIG. 2;

FIG. 4 is an end elevational view taken from the right hand of FIG. 2; and

FIG. 5 is a bottom plan view of same.

I claim:

The ornamental design for a hand mounted electrical massager, as shown and described.
